TYPEWRITING MACHINE

Walter Ettmüller, Zurich, Switzerland, assignor
to Underwood Elliott Fisher Company, New
York, N. Y., a corporation of Delaware

Application June 21, 1932. Serial No. 618,462

7 Claims. (Cl. 197—123)

This invention relates to platen-release mechanisms of typewriting machines. An object of the invention is to provide a sufficiently compact release mechanism for portable typewriters that

5 is easily operated, one that is positive in locking the platen and line-space wheel securely together, one that may be applied with minimum changes to the platen-structure as used where no release mechanism is employed and applied in such a way
10 that the platen may be readily slipped into and out of the carriage.

The usual carrying case is placed over the entire typewriter, thereby limiting the length of the typewriter-carriage, and precluding the regular 15 application of the well-known platen-release devices, since these extend the overall length of the carriage considerably.

In the Underwood portable typewriter, the line-space wheel is located close to one end of the 20 platen within the space between said platen and the side member of the platen-frame. The platen itself is of limited length (9 inches), and, for compactness, the platen-frame side members are close to the ends of the platen.

25 It is not feasible, on account of the closeness of the platen-frame side member, and the adopted organization of the line-space lever and pawl devices, to move the line-space wheel outwardly, to afford room between said wheel and the platen 30 for the platen-release mechanism. Nor is it feasible to reduce the length of the platen to afford such room, because this would correspondingly reduce the width of work-sheet which may be used.

35 Certain platen-release mechanisms heretofore evolved, are incorporated within the platen itself, and not only take up considerable room lengthwise of the platen, but require considerable modification of the platen-structure, as compared with 40 the regular structure when no platen-release mechanism is used. The platen of the Underwood portable typewriter is about 1 1/4 inches in diameter, the core of the platen being about 1 inch in diameter. A release-mechanism incorporated within the platen must be within the 45 compass of the core-diameter. If, through the use of long clutch-actuating levers extending in the direction of the platen-axis, such mechanism extends considerably into the platen, it will be 50 seen that difficulties of construction and assembly are entailed on account of the small compass of the core-diameter. It is important that the clutch be positive, that is, it must lock the platen and line-space wheel together securely, so that 55 there may be no relative rotation between the two.

Furthermore, the clutching and unclutching operation must be done with celerity, and must, therefore, be effected with little effort of the operator's fingers.

60 A clutch that, in respect to positive gripping and ease of actuation, is very efficient, is seen in the patent to Helmond, No. 1,150,366, dated August 17, 1915. In the Helmond device, the clutch-proper comprises an annular bearing surface gripped by arcuate clutch-members forcibly expanded against said surface by toggle-lever devices. In the Helmond organization, the entire clutch-mechanism is outside of the platen-frame, and its connection with the platen is through the 65 platen-knob, which is secured to the platen-shaft. The Helmond organization is only applicable where considerations of compactness are not involved, as, for example, in a standard typewriter.

70 The present application discloses a novel organization applicable to a portable typewriter, and it is contrived to work into said new organization, as clutch-elements, an annular bearing surface gripped by arcuate clutch members actuated by toggle-lever devices, all within the 75 limited compass of the portable typewriter-platen and its carriage. A portable typewriter-platen of regular length is used. The line-space wheel is maintained in its regular position, thus obviating the necessity of changing the regular line-space lever and pawl organization.

80 Within the platen-end adjacent to the line-space wheel, a shallow shell is sunk, and may be secured to the platen-core by screws, said shell having preferably an inner wall or bottom which abuts the end of said core. Against the internal 85 periphery of the shell arcuate gripping members keyed to the line-space wheel are forced to clutch said shell by toggle-lever devices. Such a clutch is by reason of the principle of the toggle-lever devices and the peripheral gripping, very efficient 90 in locking the platen and line-space wheel together, and is also easily operated to grip or let go, the clutching and releasing operation requiring little effort of the operator's fingers, notwithstanding the security with which the clutch holds. A plain platen-shaft of the small diameter requisite for free rotation may be used, and to this shaft the platen is keyed by means of a set-screw threaded through the usual hub in the 95 opposite end of the platen and seated against a flattened portion of the shaft. The platen-shaft is continuous, that is, it is in one piece, extending through and beyond the ends of the platen, so that it may be journaled in the end 100 members of the platen-frame, and so that it 105

110

projects beyond said end members, to carry at one end the usual finger-knob, whereby the platen may be rotated, and, at the other end, a knob slidable axially of the shaft. Both knobs are 5 outside of the platen-frame, that is, they are, for easy manipulation, beyond the end members thereof. By means of a thimble-cam projecting through a central opening of the line-space wheel, and slidable axially of the platen-shaft, the toggle-levers of the clutch may be spread to lock the line-space wheel and platen together, such spreading occurring when the thimble-cam is slid toward the clutch. When the thimble-cam is slid in the opposite direction, the toggle-levers 10 automatically relax and the platen is free to be rotated independently of the line-space wheel. For connecting the slidable finger-knob on the outside of the platen-frame to the thimble-cam which is within the platen-frame, a pair of pins, 15 on diametrically opposite sides of the shaft, pass through the platen-frame end member which is between the slidable finger-knob and the thimble-cam. Said pins are joined at one end to said slidable knob, and, at their other ends, 20 which are within the platen-frame, said pins are articulated with the thimble-cam in a manner to permit free rotation of said cam when said cam is entered between and therefore interlocked with the toggle-levers for the clutch. The pins 25 may have detent-grooves engageable by spring-pressed detent-devices when the thimble-cam is, by means of said pins and the slidable finger-knob at the end thereof, pushed in for locking the platen and line-space wheel together. For 30 engaging the detent-grooves in the pins, spring-pressed plungers may be used, and are retained in a suitable housing, which may be secured to the side of the platen-frame end member, and through which housing the thimble-cam engaging pins may also pass.

The toggle-levers and co-operating arcuate clutching members are keyed to the line-space wheel by means of a loose disk disposed within the shell that is sunk into the end of the platen-frame, said disk abutting the inner wall or end of said shell. For maintenance in true position the disk may have a fairly long hub rotatably fitting the platen-shaft and extending within the platen-core. A similar hub, extending with- 45 in the platen-core from the aforesaid shell which is secured to said core, may rotatably fit said disk-hub, to thereby rotatably support the clutch-end of the platen concentric with the platen-shaft. The disk has studs projecting outwardly toward 50 the end of the platen, so that the line-space wheel, which is in the form of a flat notched disk, may be attached thereto, as by screws threaded into said studs. The studs are of such length that when the disk abuts the bottom of the shell, 55 the inner face of the line-space wheel is just free of the outer rim or edge of the shell. A suitable abutment may project inwardly from the platen-frame end to prevent the line-space wheel and its attached clutch-members from creeping outwardly from said edge of the shell.

In the new organization, the platen-assembly 60 includes the platen-proper and its core with the regular hub fastened to one end, the other end having the aforesaid shell, the line-space wheel 70 forming a cover for said shell and its contained clutch. Said shell projects slightly beyond the end of the platen-proper so that the contiguous line-space wheel is in its usual position when the platen is mounted in the carriage. The 75 platen thus has the same flat end formed by the

line-space wheel as in the regular Underwood portable typewriter-platen. That is to say, there are no projections, protuberances, or other features of the organization to impede slipping the platen into and out of the platen-frame. If, with the platen in place within the frame, it is desired to withdraw the platen, all that is necessary is to loosen the set-screw in the aforesaid regular hub at one end of the platen, whereupon the platen-shaft, with its attached finger-knob, may be fully withdrawn. The central opening of the line-space wheel which surrounds the thimble-cam may be sufficiently large, so that when the platen is slightly cocked after withdrawing the shaft, it may be readily withdrawn from the platen-frame completely. The thimble-cam may also be articulated with its operating pins in such a way that when the platen-shaft on which said thimble-cam is slidably supported is withdrawn, said cam is capable of a floating movement about its connections with said pins, which conduces to the ease with which the platen may be completely withdrawn.

Other features and advantages will hereinafter appear.

In the accompanying drawing,

Figure 1 is a longitudinal view of the platen showing the end-portion of the platen and platen-frame in which the novel platen-release organization is embodied in section.

Figures 2 and 3 are end-views of the platen, Figure 2 showing the clutch-members in released position so that the platen may be rotated independently of the line-space wheel, and Figure 3 showing the clutch-members expanded so that the clutch is effective to lock the line-space wheel and platen together.

Figure 4 is a view similar to Figure 1 and shows the thimble-cam and its operating parts pressed in to expand the clutch-members.

Figure 5 is a perspective view of the assembled platen-release mechanism, certain parts being shown in section to illustrate the novel organization.

Figure 6 is a view illustrating how the thimble-cam may be snapped over the operating pins which project through the side of the platen-frame.

Figure 7 is a perspective view showing the parts of the platen-release organization spread out to bring out details of said parts.

Figure 8 is a detail view of a block for housing detent-devices for the thimble-cam.

The platen-frame of the Underwood portable typewriter includes a left end member 10 and a right end member 11 in which there is journaled a platen-axle 12. A cylindrical platen 13 has a core 14, to the right end of which is secured, in the usual manner, a flanged hub 15. By means of a set-screw 16, threaded into said hub and tightened against a flattened portion 17 of the platen-shaft 12, the assembled platen is keyed to the platen-shaft. The right end of said shaft 12 carries the usual finger-knob 18 for rotating the platen by hand.

The core 14 of the platen is shortened to form an annular recess within the left end of the platen in which there is received a shell 19, said shell having a long hub 20, fitting an enlargement of the central opening of the core 14, and also having an inner wall 21 through which pass screws 22 for fastening said shell 19 to said core. The shell 19 is of the same outer diameter as the core 14 to form a continuous cylindrical surface with the latter upon which the platen-proper is 150

formed. A line-space wheel 24 is in the form of a toothed circular disk which is concentrically mounted with the platen-axis by means of a disk 25 having a long hub 26 fitting within the shell-hub 20 and over the platen-shaft 12, the fit being loose so that the hub 20 and shaft 12 may be rotated relatively to the disk 25 and its hub 26. The disk 25 normally abuts the wall 21 of the shell 19, the surface of said wall being relieved as at 27, so that the disk 25 bears only against an outer rim of said wall. Projecting from the disk 25 is a pair of diametrically opposite studs 28, to which the line-space wheel 24 is secured by screws 29, whose heads are countersunk below the outer surface of said line-space wheel. Of the driven and driving members of the clutch-mechanism, the shell 19 keyed to the platen 13 forms one member and the line-space wheel 24 keyed to the disk 25 forms another member. For releasably connecting the two members, there is within the clutch a pair of arcuate members 30, one end of each of which abuts a block 31 projecting from the disk 25 and fastened thereto by dowels 32. From the block 31 the clutch-members 30 extend circumferentially around the inner surface of the shell to an extent which affords, between the other ends of said arcuate members 30, a space in which there plays a toggle formed by arms 33 of a pair of levers 34, as seen in Figures 2 and 3. The middle joint of said toggle is formed by a floating pin 35 that is articulated with conforming recesses in the inner opposite ends of the toggle-arms 33. The outer ends of the toggle-arms 33 are similarly articulated with the respective ends of the arcuate members 30 by pins 37, these latter pins also floating. It will be seen from Figure 3 that with the arcuate members 30 reacting at one end against the block 31, and with the toggle-arms 33 almost straightened out, the clutch-members 30 will be powerfully forced against the annular surface of the shell 19 and the platen and line-space wheel will therefore be securely locked together. Conversely, if the toggle is relaxed or broken as in Figure 2, the clutch-members 30 will not grip the annular surface of the shell 19 and the platen may then be rotated independently of the line-space wheel. For straightening and breaking the toggle formed by the arms 33, the levers 34 have arms 36 which extend symmetrically to opposite sides of the platen-shaft 12, as seen in Figures 2 and 3. For retaining the arcuate members 30, the toggle-levers 34, and associated pins 35 and 37 against the disk 25, there is provided a disk 39 having openings 40 to fit over the studs 28. To clear the inner surface of the shell 19, said disk is of a somewhat smaller diameter than said surface. Said disk also has a deep notch 41, so that when it is in place, it clears the block 31 and also a thimble-cam 42. For holding the disk 39 in position to retain the clutch-parts, it may be spaced from the line-space wheel 24 in any suitable manner, as, for example, by sleeves or springs 43 (Figure 7) surrounding the studs 28, one end of said springs abutting the line-space wheel 24 and the other ends abutting the retaining disk 39. Said disk 39 and springs 43 are not included in Figure 5, being omitted for the sake of clearness.

The thimble-cam 42 may be slidable along the platen-shaft 12 and its periphery may be formed so as to spread the levers 34 when said thimble is pushed inwardly between the arms 36 of said levers, as seen in Figure 4, and conversely to

release said levers when said thimble-cam 42 is pushed outwardly to the position seen in Figure 1. In order that the thimble-cam 42, which is between the end of the platen and left end member 10 of the platen-frame, may be operated from a point outside said platen-frame to release or engage the platen-clutch, means are provided which include a finger-knob 44 slidable along the platen-shaft 12. Projecting from the inner face of said knob are a pair of pins 45 on opposite sides of the platen-shaft, said pins passing through the platen-frame end member 10, and also through a block 46 which may be secured to said end member 10 by a screw 47 and a dowel 49. The pins 45 may have a sliding fit in the end member 10 and the block 46. For connecting the thimble-cam 42 with the pins 45 so that movement of the finger-knob 44 along the platen-shaft 12 will effect a corresponding movement of said thimble-cam 42 to release or engage the platen-clutch, the thimble-cam has a flange 50 having formed therein an annular groove 51. Said groove embraces heads 52 formed on the pins 45 by grooves 53, the outer side of the thimble-cam groove 51 overlapping the inner side of said heads 52 of the pins 45. Assembly of the thimble-cam 42 over said heads 52 of the pins may be effected, as indicated in Figure 6, by springing or bending the pins 45. An alternative way of assembling said thimble-cam 42 over the pins 45 is to first assemble said pins within the groove 51, then to thrust said pins through the end member 10 and block 46, and finally to assemble the finger-knob 44 over the outer ends of the pins, said pins being then secured to said finger-knob 44 in any suitable way, as, for example, by riveting over their outer ends 55.

For adjusting the force with which the arcuate clutch-members 30 grip the annular surface of the shell 19, the ends of said members which abut the block 31 are spread more or less by expansion or contraction of the block itself. The block has, therefore, a kerf 56 bisecting a hole, into which a taper-screw 57 is threaded. Due to the taper of said screw, the block will be more or less expanded, depending on how far the screw is entered into the hole. For locking the screw 57, a transverse screw 58 is provided, said screw passing through a tongue 59 projecting beyond the clutch-members 30, levers 34 and the retaining plate 39, as seen in Figures 1 and 4. The withdrawal of the thimble-cam 42, to unlock the platen, may be limited by its abutment with a hub 60, which may be formed integral with the platen-frame end member 10, as seen in Figure 1. Inward movement of the thimble-cam 42, for locking the line-space wheel and platen together, may be limited by abutment of the flange 50 of said cam with the outer face of the line-space wheel 24, as seen in Figure 4. In moving the thimble-cam inwardly, the ends or heads of the pins 45 push against the bottom of the depression within whose annular edge the groove 51 is formed. When the thimble-cam has been pushed in to lock the platen and line-space wheel together, it may be maintained in position by a suitable detent-device, as, for example, by steel balls 62 pressed into grooves 63 of the pins 45, each ball 62 being pressed against its pin by a spring 64 backed up by a screw 65. As indicated in Figures 1 and 4, the balls 62, springs 64 and screws 65 are contained in the aforementioned block 46 that is secured to the outer side of the platen-

frame end member 10. The block 46 may have holes 66 arranged as shown in Figure 8, into which the steel detent-balls 62 are first inserted and depress springs 64, the outer ends of said holes having a threaded portion 69 for the screws 65. For preventing the line-space wheel 24 and its attached clutch-parts from creeping outwardly from the shell 19, there may extend inwardly from the platen-frame end member 10 a suitable projection or stud 67 as indicated in Figure 1.

Withdrawal of the entire platen is easily effected when the platen-shaft 12 is withdrawn. Said shaft may be withdrawn when the set-screw 16 is loosened. A slight cocking of the platen when the shaft is withdrawn will bring its end clear of the hub 61 of the right platen-frame end member 11, after which the entire platen may be withdrawn without hindrance. Conducting to ease of platen-withdrawal is a sufficient enlargement of the hole 68, whereby the line-space wheel 24 clears the thimble-cam 42. Also conducting to ease of withdrawal of the platen is the capability which the thimble-cam 42 has of floating about its points of attachment with the pins 45 when the platen-shaft 12 has been withdrawn. Withdrawal of the platen being thus easily effected, it may with similar ease be put back into the platen-frame again, whereupon the platen-shaft 12 may be easily inserted and the set-screw 16 tightened. In withdrawing the platen from the typewriter, it is moved upwardly and forwardly, and, in order that the thimble-cam may float in a corresponding direction when the platen is withdrawn, the pins 45 are placed along an oblique line, as indicated in Figures 5 and 7. For the same reason, the stud 67 may also be placed on or below said line.

Co-operating with the line-space wheel 24, for holding the platen in line-space positions, is the usual spring-pressed detent-arm 70, which engages notches 71 in the rim of the line-space wheel.

It will be noted that the platen-journals are no larger than the platen-axle 12 itself, thus conducting to free rotation of the platen, which enables the spring-pressed line-space detent-arm and roll 70 to accurately locate the platen by means of the line-space wheel detent-notches 71. After the thimble-cam 42 has, by means of the pins 45, been pushed in until it abuts the line-space wheel 24, the detent 62 may cause a slight retraction of said pins 45, so that the rounded ends of said pins do not bear against the bottom of the depression forming the groove 51 of the thimble-cam 42. The thimble-cam is made of steel and hardened and the bottom of said depression may be polished. Similarly the ends of the pins 45 may be hardened and polished to obviate friction. It will be understood that other clutch-parts that are subject to wear may be made of steel and hardened.

It will also be noted that the only change or modification of the platen-structure required to accommodate the novel platen-release-mechanism organization is the shortening of the core 14 and the enlargement of its central opening, so that the shell 19 and its hub 20 may be received in the end of the platen. There is no weakening of the core-structure to preclude the use of the usual wooden core. When the platen is withdrawn from the typewriter, it is to all appearances like the regular portable typewriter-platen, the line-space wheel 24 being in the same position relatively to the end of the platen as

in the regular platen, and, moreover, presenting the same flat left end of the platen. The opposite end of the platen has, as already mentioned, the regular hub 15.

Variations may be resorted to within the scope of the invention, and portions of the improvements may be used without others.

Having thus described my invention, I claim:

1. The combination with a platen-frame having ends, a platen-shaft journaled in and spanning said ends, a rotary platen keyed to said shaft and located between the frame-ends, and a loose line-space wheel between one end of the platen and a frame-end, of clutch-mechanism including means mounting said wheel concentric with said shaft and also mounting one end of the platen, so that the platen may be rotated independently of said wheel, said clutch-mechanism being housed between the line-space wheel and one end of the platen, and means including a finger-piece operable from a point outside the clutch-end of the platen-frame, said latter means arranged to pass said frame in spaced relationship from the shaft, so that the shaft itself is journaled directly in said frame-end. 85 90 95 100

2. A revoluble platen-assembly including a core somewhat shorter than the platen, so as to form in one end of the platen a shallow recess, a shell within said recess forming a continuation of said core and also forming an annular surface, a loose disk at the inner end of said shell, having projections spaced from the center of the disk and extending toward the outer end of said shell, a line-space ratchet-wheel mounted on said projections and forming a cover for said shell, said shell, disk and platen being arranged for rotation of said platen and its shell relatively to said wheel, a pair of diametrically opposite gripping members conforming to said annular shell-surface, said loose disk having a projection abutting one end of each of the gripping members, said members forming a space at their other ends, and a pair of levers having arms forming a toggle for spreading the spaced ends of said members to cause them to grip said surface, said levers also having operating arms extending toward opposite sides of the platen-axis, said gripping members and levers arranged in a common plane against said disk, said line-space wheel having a central opening for the insertion of means for spreading said operating arms. 105 110 115 120 125 130

3. In a portable typewriter, the combination with a platen-frame having ends, a rotary platen, and a one-piece platen-shaft journaled in said ends, of a loose line-space wheel between one end of the platen and the platen-frame-end, clutch-mechanism between said wheel and the end of the platen for releasably locking said platen and wheel together, a thimble-cam slidable along said shaft for actuating said clutch-mechanism, and located between the end of the platen and the platen-frame-end, a finger-knob slidable on said shaft outside of the platen-frame-end, pins passing said platen-frame-end, and connecting said knob and thimble-cam, and detent-devices mounted on said frame-end and effective for detenting said cam when the platen and line-space wheel are locked together. 135 140 145

4. In a portable typewriter, the combination with a platen-frame having ends, a rotary platen, and a one-piece platen-shaft journaled in said ends, of a loose line-space wheel between one end of the platen and the platen-frame-end, clutch-mechanism between said wheel and the end of the platen for releasably locking said platen and 150

wheel together, a thimble-cam slidable along said shaft for actuating said clutch-mechanism, and located between the end of the platen and the platen-frame-end, a finger-knob slidable on said shaft outside of the platen-frame-end, pins passing said platen-frame-end, and connecting said knob and thimble-cam, and spring-pressed detents mounted in said frame-end and engaging detent-grooves in said pins for detenting said 10 cam when the platen and line-space wheel are locked together. 85

5. In a portable typewriter, the combination with a platen-frame having ends, a rotary platen, and a platen-shaft journaled in said ends, of a 15 loose line-space wheel between one end of the platen and the platen-frame-end, clutch-mechanism between said wheel and the end of the platen for releasably locking said platen and wheel together, a thimble-cam slidable axially 20 of said shaft for actuating said clutch-mechanism and located between the end of the platen and the platen-frame-end, a finger-knob slidable axially of said shaft outside of the platen-frame-end, said cam having a flange forming a peripheral groove, and pins projecting inwardly from 25 said knob and passing said platen-frame-end, said pins formed at their inner ends for articulation with said groove in a manner to permit rotation of said cam when said cam is interlocked 30 with said clutch. 105

6. The combination with a rotary platen and a loose line-space wheel, of a shell fastened to and sunk into one end of said platen to form an annular bearing surface, a pair of arcuate clutch-members for gripping said surface, a pair of levers 35 having arms forming a toggle between spaced ends of said clutch-members, a loose disk within said shell, spaced from the outer end thereof and 110 line-space wheel is fastened. 110

having a projection against which the other ends of said clutch-members abut, said projection having a kerf so that it may be more or less expanded to adjust the grip of said members, a wedge in said kerf for so adjusting said projection, and a transverse screw for drawing the split portions of said projection together to lock said wedge in adjusted position, said disk having other projections extending outwardly, and to which said line-space wheel is fastened to form a cover for said shell. 80

7. The combinations with a rotary platen and a loose line-space wheel, of a shell fastened to and sunk into one end of said platen to form an annular bearing surface, a pair of arcuate clutch-members for gripping said surface, a pair of levers having arms forming a toggle between spaced ends of said clutch-members, a loose disk within said shell, spaced from the outer end thereof and having a projection against which the other ends of said clutch-members abut, said projection having a kerf so that it may be more or less expanded to adjust the grip of said members, a wedge in said kerf for so adjusting said projection, a transverse screw for drawing the split portions of said projection together to lock said wedge in adjusted position, said projection extending beyond said members and levers, so that said locking screw is accessible, and a removable plate within said shell for retaining said members and levers against said disk, said line-space wheel forming a cover for the outer end of said shell, and being spaced from said members and levers on account of the extension of said projection, said disk having other projections to which said line-space wheel is fastened. 90 95 100 105 110
